UNITED STATES PATENT OFFICE

JOHN SCHADE, OF HOLYOKE, MASSACHUSETTS, ASSIGNOR TO NATIONAL BLANK BOOK COMPANY, OF HOLYOKE, MASSACHUSETTS, A CORPORATION OF MASSACHUSETTS

LOOSE-LEAF BINDER

Application filed July 27, 1929. Serial No. 381,412.

This invention relates to loose leaf binders that are composed of two sections hinged together at the bottom and that have curved prongs for the sheets contained within the book.

The object of the invention is to provide such a construction as will enable sheets to lie flat against the covers without opening the sections.

In books of this type, in order that the sheets may lie substantially flat for writing purposes it has been necessary to open the book to such a degree as would cause the prongs to be partially disengaged from many of the sheets, when the latter are shifted from one side of the book to the other, but the present invention overcomes this defect by securing the prongs to the hinge sections in such a manner that the sheet-containing portions of the prongs are wholly above said sections.

In the accompanying drawings which form a part of this application

Figure 1 is an inside view of the book with the sections closed and the covers broken away and open—

Figure 2 is a similar view with the sections open—

Figure 3 is a side elevation of the book with the cover and fiber facing of the side broken away—

Figure 4 is a section at the line 4—4 of Figure 1 with the curved prongs in elevation—

Figure 5 is a section at the line 5—5 of Figure 1—

Figure 6 is a section at the line 6—6 of Figure 2, and

Figure 7 is a section at the line 7—7 of Figure 1 showing leaves or sheets opened and lying substantially flat against the covers.

Similar numerals of reference denote like parts in the several figures of the drawing.

1, 2, are the sections of the book having at the inner edges of their bottom portions hinge eyes 3, 4, which are alined and a pintle 5 inserted therethrough.

6, 7, are the ends of these sections 1, 2, which ends closely abut each other when the sections are closed.

8, 9, are the sides of these sections 1 and 2 which rise substantially at right angles from

the bottom of the sections, and the upper edges of these sides are curled outwardly and then downwardly in a vertical line, as shown at 10 and 11, these curled edge portions being cut away at 12 and 13, for the purposes 55 presently to be explained. At one end of the sections a latch lever 14 is pivoted at 15 to the inside face of one end of the section 1, and has a finger piece 16 which extends upwardly and overhangs the upper edge of this end, 60 and a wire spring 17 is coiled around the pivot 15 and one terminal is secured over a pin 18 that extends from the latch lever 14 while the other terminal bears against the inner face of the side 8, the function of this spring 65 being to normally force the latch lever downwardly in engagement with a stud 19 that extends from the inner face of the adjacent end 7 of the section 2, as shown at Figure 5, where the sections are shown locked 70 together by means of this latch lever.

When the latch lever is released by depressing the finger piece 16, and the sections opened as shown at Figure 6, this lever will, by the force of the spring, strike against one 75 of the hinge portions at the bottom of the sections, so as to prevent the end of this latch lever from getting out of the field of engagement with the stud 19 when the sections are closed.

20 are the curved prong members that extend from the section 1, and 21 are the similar members that extend from the section 2.

These curved prong members extend wholly above the curled portions 10 and 11 of the respective sections and are comparatively straight immediately above said portions, and have straight base terminals 22 and 23 which extend through these curled edges and lie flat 85 against the outer faces of the sections and are firmly secured thereto, preferably by extending them at an angle through the sides of the sections and riveting them thereto, as shown at 24 and 25, and the curved portions 90 of these prongs slightly above the edges 10, 11, coincide with curves described from the hinge center of the sections 1 and 2.

26 and 27 are the side covers which have hing plates 28 and 29 that are secured in any 100

suitable manner to the covers, and these hinge plates are provided at their inner ends with hinge eyes 30 and 31 through which are inserted short pintles 32 and 33 which project beyond the hinge eyes and are housed within the curled portions 10, 11, with the hinge eyes occupying the cut-away portions 12 and 13.

In order to prevent the pintles from dropping free of these curled or curved portions 10 and 11, blocks 34, 35, of any suitable material, are placed immediately beneath the hinge eyes 30 and 31, and these blocks are secured to the sides of the sections, or held in place by fiber facings 36 and 37 which are secured to the bottoms and sides of the sections 1 and 2.

The side covers are composed of thick facings 26 and 27 which really constitute the actual covers, and to which the hinge plates 28 and 29 are secured.

It will thus be clearly seen that all of the sheet-retaining portions of the curved prongs are wholly above the side edges of the book, so that when these sheets *a* are thrown outwardly, as shown at Figure 7, they will lie flat against the open covers when the sections are fully closed, and this also enables the leaves that are on the prongs to be thrown back and forth from one side of the book to the other without the slightest danger of becoming freed from the prongs, as would be the case if the sets of prongs were open.

The nose of the latch lever 14 is beveled so that it will engage the stud 19 and be raised and allowed to be forced into latching engagement therewith when the sections are closed.

But it is not necessary to open the sections, as shown at Figures 2 and 6, except for the purpose of removing or adding sheets.

This disposition of the curved prong members overcomes the disadvantages of constructions heretofore used in which the lower leaf-holding portions of said members are below the sides of the book, since in this latter instance the leaves must rise upwardly and pass over said sides before they can lie against the side covers, thus rendering writing on the leaves difficult, laborious and unsatisfactory.

What is claimed is:—

1. A loose leaf binder, comprising two sections hinged together at their backs and having upstanding sides the upper edges of which are curved outwardly and downwardly and have spaced cut-away portions, side covers having hinge plates, said plates having hinge eyes located within said cut-away portions and short pintles therein which are housed within said curved edges, blocks beneath said eyes and secured to said sides, and curved prongs secured to said sides and extending upwardly and then inwardly toward each other in parallelism, the leaf-holding por-

tions of said prongs being wholly above said sides.

2. A loose leaf binder, comprising two sections hinged together at their backs and having upstanding sides which are curved outwardly and downwardly at their upper edges, prongs projecting upwardly from said curved portions and terminating in curves described from the center of said hinge, the lower ends of said prongs terminating in bent portions which pass through said sides and are riveted thereto.

In testimony whereof I affix my signature hereto.

JOHN SCHADE.
